UNITED STATES PATENT OFFICE.

CLAUDE P. LA SHELL AND WALTER A. BEHRENS, OF NEW YORK, N. Y.

CHAIN GUIDE.

Application filed September 2, 1921. Serial No. 498,105.

Our invention relates to a pull socket, and particularly to means for guiding the pull chain.

It is an object of the invention to provide 5 novel means for accurately positioning the chain guide with relation to the parts operated thereby.

It is a further object to provide a chain 10 guide held between the switch carrying block and the socket shell and which will be prevented from longitudinal movement relative to the block by means independent of the enclosing shell.

In the preferred form of our invention 15 there is provided a socket shell enclosing switch mechanism to be operated by a pull chain. A chain guide is positioned between the enclosing shell and the switch carrying block and chain guide have co-operating means for accurately positioning the chain guide relatively to the switch operating parts.

In the drawings we have shown a preferred form of our invention.

Fig. 1 is a view in elevation of a lamp socket embodying features of our invention.

Fig. 2 is a similar view of the interior of 30 a lamp socket showing our improved chain guide positioned relatively to the switch block.

Fig. 3 is a partial vertical sectional view of the shell body and interior parts.

Fig. 4 is an enlarged detail perspective 35 view of one form of our improved chain guide.

The pull socket includes the usual shell body 5 and cap 6 suitably held thereon. The body is provided with a slot 7 through which 40 projects part of the chain guide 8. The switch mechanism within the shell is operated by means of a suitable member such as a chain 9 extending through the chain guide.

The interior of the socket may comprise 45 a switch carrying block which is usually made in two parts 10-11 suitably secured together and holding the switch operating mechanism therebetween. The switch operating mechanisms for pull sockets are well known in the art and therefore no detailed disclosure thereof has been made in the present application. The pull chain 9 is secured to the oscillating member 12 and serves to

oscillate the latter for making and breaking 55 the circuit as will be understood by those skilled in the art.

The chain guide 8 preferably comprises a base plate or portion 13 and a bell 14. The bell and base plate are usually separately 60 formed and afterwards secured together in any suitable manner. In the form shown, the switch carrying block is provided with a boss or lug 15 at one side. The base plate of the chain guide has one or more fingers 16-17 and a suitable edge or surface 18 therebetween. The fingers 16-17 loosely fit the sides of the lug 15 and prevent relative sidewise movement between the chain guide and switch block. The edge or surface 18 may engage a part of the block, preferably the under side of the lug thereon, for preventing upward movement of the chain guide relatively to the switch block. We also provide means for preventing downward 65 longitudinal movement of the chain guide. In the form shown, extending from one or both of the fingers is a part or projection 19 which may engage the upper end of the lug for preventing downward longitudinal 70 movement of the chain guide. The parts just described may be conveniently formed by providing an aperture 20 in the base plate. This aperture 20 and the lug 15 preferably correspond in shape though the 75 aperture is of such size as to be readily accommodated by the lug.

When the parts are to be assembled the chain guide is set in place with the aperture receiving the lug. The parts are then slid 80 into the body of the shell with the base plate preferably extending between the switch carrying block and the body of the shell. The slot 7 in the shell is open at the top to permit the insertion of the projecting chain bell 85 and lug. The cap is then applied to the shell body and the assembly is complete. The lug acts as a positioning means for the chain guide and the latter is dependent upon, and co-acts with, the shell whereby the latter 90 holds the chain guide in place.

It is obvious that if for any reason there is a tendency of the switch block to be moved longitudinally within the shell, the chain guide will restrain the block and therefore 105 the chain will always be guided and in proper position to operate the interior switch parts.

It will be noted that the chain guide is not attached to either of the members but is held between the interior block and the shell, but when the parts are assembled, the 5 guide is accurately positioned with relation to the interior switch.

The term "chain" has been used herein to define any element for operating the switch. While chains are usually used for 10 operating pull switches, obviously other members may be used.

While we have described in great detail one form of our invention, we do not wish to be limited to the form shown, for obviously, many changes may be made under 15 the following claim.

We claim:

A pull socket comprising an insulating body having a lug integral therewith and 20 projecting outwardly therefrom near its up-

per edge, a chain guide having a base plate loosely fitting against the outer wall of the body and having an opening through which said lug extends and a cross bar overstanding the upper edge of said lug and a shell 25 enclosing said body and base plate, said shell consisting of a body having a slot into which said lug extends to prevent relative rotation of the body and shell and a cap covering the outer end of said lug, said lug and base plate 30 being so interlocked as to prevent the chain guide from shifting on said body in any direction except in a direction at right angles to said body when said shell is removed, said chain guide being readily removable in a direction at right angles to 35 the surface of the body at said lug when the shell is removed.
